(57) **CLAIM**

The ornamental design for a coffee bean tester as shown and described.

DESCRIPTION

FIG. 1 is a front elevational view of a coffee bean tester showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a first perspective view thereof; and,

FIG. 8 is a second perspective view thereof.

The broken lines shown in the drawings are for the purpose of illustrating portions of the coffee bean tester that form no part of the claimed design.
